UNITED STATES PATENT OFFICE.

JOHN C. McLAUGHLIN, OF JERSEY CITY, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

No. 907,632.

Specification of Letters Patent.

Patented Dec. 22, 1908.

Application filed May 16, 1908. Serial No. 433,169.

To all whom it may concern:

Be it known that I, JOHN C. McLAUGHLIN, a citizen of the United States, residing in Jersey City, in the county of Hudson and 5 State of New Jersey, have invented certain new and useful Improvements in Type-Writing Machines, of which the following is a specification.

This invention relates to the pawl and 10 ratchet mechanism for effecting the line-feeding movements of platens of typewriting machines.

It is usual to employ a spring detent to engage the ratchet wheel to position the platen 15 accurately for successive lines, and also to hold the platen steady during the writing of each line.

It often happens, when a nervous operator 20 gives an unusually quick stroke to the lever which operates the platen-driving pawl, that the platen overthrows. This is due principally to the weight of the platen, the usual spring detent being insufficient to arrest the platen at the proper point when the platen 25 has received unusually great impetus from the jerky stroke of the spacing lever. The platen is sometimes overthrown only a portion of a line-space, and during the writing of a line it sometimes happens that the spring 30 detent, acting upon the teeth of the ratchet wheel, gradually forces the platen back to its proper position; such gradual back rotation of the platen having the effect to cause the written letters to form a curved or slanting 35 line instead of a straight line across the page.

The object of the present invention is to provide simple and inexpensive means for overcoming this disadvantage, particularly 40 with a view to applying the device to existing machines.

In the Underwood typewriting machine, the platen detent is in the form of a spring-pressed lever, having a roll to engage the teeth of the ratchet wheel. I provide upon 45 this lever an extension or arm which I cause to arrest the platen-rotating lever and pawl; and the device is so contrived that the shock received by the detent at the arrest of the operator's hand serves to press the detent more 50 forcibly into the notch in the line-space ratchet wheel. Thus the greater the force imparted to the line-space lever, or the quicker the stroke of said lever, the greater is the power applied to the line-space wheel.

to check the rotation of the platen, so that 55 overthrow is avoided.

In the accompanying drawings, Figure 1 is a perspective view of the line spacing mechanism of an Underwood typewriting machine, with my improvements applied 60 thereto; the parts shown in their positions at the arrest of the line-spacing pawl and the platen. Fig. 2 is a plan showing the line-space pawl-carrying slide in engagement with the platen-arresting or locking means. Fig. 65 3 is a view similar to Fig. 2, but showing the line space lever in normal position and out of engagement with the platen-arresting means. Fig. 4 is an end elevation of the line-spacing mechanism, showing the parts in operative 70 or stroke-arresting positions.

Type-bars 1 strike on the front of a platen 2, which is rotatably mounted by means of an axle 3 in platen frame ends 4, and carries a notched line-space wheel 5. Upon a slide 6, 75 mounted for backward and forward sliding movement upon the platen frame end 4, is pivoted a pawl 7, which is forced into engagement with the notches of the wheel 5 by a spring 7^a, whenever a backward movement is imparted to said slide by the usual lever 8, to rotate the platen. As usual, the slide is returned forwardly to normal position by a spring 9, and simultaneously the pawl 7 is withdrawn from the wheel 5 by 85 means of a nose 10 on the pawl, said nose riding upon a trip 11 formed upon a plate 12, which is pivoted at 12^a to and is adjustable 90 backwardly and forwardly by a finger-lever 13, for the purpose of regulating the line-spacing of the platen. A detent lever 14 is pivoted at 14^a upon the platen frame end 4, having a roll 15 which by means of a spring 15^a is normally pressed into one of the notches of the wheel 5 to hold the platen 95 steady during writing. As so far described, the parts are in common use on the Underwood typewriting machine.

I provide the detent 14 with a stop or arm 16 projecting up into the path of the slide 6, 100 to be engaged by a projection 17 upon said slide at the termination of a line-space stroke of the operating lever 8. The shock of arresting the lever stroke forces the arm 16 backward and crowds the detent roll 15 forward forcibly into the notch in the wheel 5, to lock the platen; so that the quicker the stroke of the lever 8, the more powerful is the 105

detent 14 to arrest the wheel and platen; whereby liability of overthrow of the platen is avoided.

Variations may be resorted to within the scope of the invention.

Having thus described my invention, I claim:

1. In a typewriting machine, the combination with a revoluble platen provided with a line-space wheel, of a detent constantly pressed by a spring against said line-space wheel, a pawl to engage the wheel to rotate the platen, and a stop to arrest the pawl at the termination of a line-space stroke, said stop connected to said detent to cause the latter to lock the platen against overthrow.

2. In a typewriting machine, the combination with a revoluble platen, of a line space wheel connected to the platen, a spring detent for the wheel and platen, and a slide having a pawl and operable by a lever to rotate the wheel and the platen, and means to enable said slide to coöperate with the detent to check or lock the platen and prevent overthrow thereof.

3. In a typewriting machine, the combination with a revoluble platen, of a line-space wheel therefor normally engaged by a spring detent, and a slide operable by a lever to rotate the platen; said detent having a part projecting into the path of the slide to be engaged thereby to force the detent against the wheel.

4. In a typewriting machine, the combination with a platen and a notched line space wheel therefor, of a slide or carrier provided with a pawl normally out of engagement with the wheel, a lever to operate the slide and cause the pawl to rotate the platen, and a spring detent pivoted upon the platen frame and comprising both an arm having a roll normally engaging the line space wheel and an arm to be engaged by a projection on the slide at the termination of a line - space stroke, to force the roll into the notch in the wheel to check or lock the platen against overthrow.

5. In a typewriting machine, the combination with a revoluble platen having a line-space wheel engaged by a spring detent, and a slide having a pawl and operable by a lever, of means to prevent overthrow of the platen, comprising a stop projecting into the path of and engaged by the slide, said stop co-acting with the detent to force the detent against the line space wheel and lock the platen.

6. In a typewriting machine, the combination with a revoluble platen, a line space wheel therefor, and a lever-operated slide having a pawl to engage the wheel to rotate the platen, of a stop mounted on the platen frame in the path of said slide to be engaged thereby at the termination of the line-space

stroke, and means for enabling said stop to lock the platen against overthrow.

7. In a typewriting machine, the combination with a revoluble platen and a line-space wheel therefor, of a spring detent to engage the line-space wheel, a lever-operated slide carrying a pawl to turn said wheel and platen, and means to enable said slide to augment the force with which the detent engages the wheel at the termination of the platen-operating stroke of the lever.

8. In a typewriting machine, the combination with a revoluble platen and a line-space wheel therefor, of a spring detent to engage the line-space wheel, a lever and pawl to turn the wheel and platen and a stop for the lever; means being provided to enable the lever acting through said stop to augment the power of the detent.

9. In a typewriting machine, the combination with a revoluble platen provided with a line-space wheel, of a pawl to engage the wheel to rotate the platen, driving means for said pawl, a stop to arrest the pawl at the termination of the line-space stroke, said stop mounted on the platen frame independently of the line-space wheel and of the pawl driving means, and means operated by said stop to lock the platen against overthrow.

10. In a typewriting machine, the combination with a revoluble platen, of a line-space wheel connected to the platen, a spring detent normally engaging the line-space wheel, a pawl to drive the line-space wheel, a lever to drive the pawl, and means to enable said lever to actuate said detent to check or lock the platen against overthrow.

11. In a typewriting machine, the combination with a revoluble platen, of a line-space wheel therefor, a spring detent normally engaging said line-space wheel, a lever having means to rotate the platen, and a part upon said detent projecting into the path of said rotating means to be engaged thereby to force the detent against the wheel.

12. In a typewriting machine, the combination with a platen and a notched line-space wheel therefor, of platen-rotating means including a pawl normally out of engagement with the wheel, a lever having means for driving the pawl to rotate the platen, and a spring detent pivoted upon the platen frame and comprising both an arm normally engaging the line-space wheel and an arm to be engaged by a member on said platen-rotating means at the termination of the line-space stroke, to force the spring detent against the line-space wheel to check or lock the platen against overthrow.
